(57) **CLAIM**

The ornamental design of a “lamp head for light fixtures,” as shown and described.

DESCRIPTION

FIG. 1 is a front, right perspective view of an example “lamp head for light fixtures” in accordance with our new design disclosed herein;

FIG. 2 is a front view of the example lamp head of FIG. 1; FIG. 3 is a back view of the example lamp head of FIG. 1; FIG. 4 is a right side view of the example lamp head of FIG. 1;

FIG. 5 is a left side view of the example lamp head of FIG. 1; FIG. 6 is a top view of the example lamp head of FIG. 1; and, FIG. 7 is a bottom view of the example lamp head of FIG. 1. The portions shown in broken lines are for illustrative purposes only and form no part of the claimed design.
